AUTOGRAPHIC REGISTER

Louis Jensen, Chicago, Ill., assignor to United
Autographic Register Co., Chicago, Ill., a cor-
poration of Illinois

Application November 14, 1932, Serial No. 642,643

19 Claims. (Cl. 282—21)

This invention relates particularly to auto-graphic registers and to improved mechanism for engaging and advancing continuous-form stationery over the platen of the machine after a set 5 of forms have been filled in.

The primary object of the invention is to provide a simple but improved register of the hand pull-out type having register-pins which engage perforations in the stationery and are withdrawn 10 from the perforations and returned to strip engaging position after the strips have been advanced to a position where their ends may be grasped by hand.

The invention is illustrated in the preferred 15 embodiment in the accompanying drawings, in which—

Fig. 1 is a perspective view of a register embodying the invention; Fig. 2, a longitudinal sectional view taken as indicated at line 2 of Fig. 4; 20 Fig. 3, a broken sectional view similar to Fig. 2, showing the register-pins in advanced position; Fig. 4, a sectional view taken as indicated at line 4—4 of Fig. 2; Fig. 5, a broken longitudinal sectional view of a modified form of feed device; 25 Fig. 6, a broken elevational view of the same; Fig. 7, a broken plan view showing one corner of the register illustrated in Figs. 5 and 6; Fig. 8, a broken longitudinal sectional view of another modification; Fig. 9, a sectional view similar to 30 Fig. 8, showing the pins in advanced position; Fig. 10, a broken sectional view taken as indicated at line 10 of Fig. 8; and Fig. 11, a broken longitudinal sectional view showing still another modification.

35 In the preferred embodiment of the invention A designates a casing having a bottom wall A', a platen-forming top wall A², and a rear wall A³ serving as a door to the supply compartment thus formed; B, a skeleton cover provided at its front 40 end with a tear-off bar B'; C, presser-mechanism; and D, initial feed-mechanism.

The casing A may be of any suitable construction, and is shown with a front wall 12 attached to the bottom wall A' by means of screws 12^a. A front abutment member 13 and a rear abutment member 15 are also attached to the bottom wall A' and serve to hold a packet of stationery 14 in position in the casing. A guide roll 16 is journaled in side walls 17 of the casing and serves to direct stationery strips 14^a from the packet 14 to the platen of the machine.

The top wall A², or platen, is rigidly connected to the side wall 17 and its front end portion 18 is curved downwardly and provided with slots 18^a through which register-pins may project.

The rear door A³ is hinged at 19 to the side walls of the casing. The door is provided with a rigidly connected guide bar 20 which supports the strips 14^a near the guide roll 16.

The skeleton cover B has a cut-out portion 21 which exposes stationery led over the platen A². The cover is provided with a downwardly extending flange 22 which is pivoted to the side walls 17 by means of screws 23 and swings down over the casing of the machine. The rear portion of the flange is provided with a forwardly projecting boss 22^a which is adapted to engage a recess 24 in the door A³ and yieldingly hold the rear end of the cover in position. A projection 22^b is provided to facilitate raising the cover. 70 The tear-off bar B' may be formed by turning a portion of the metal from the opening 21 forwardly to form a double thickness. The front end, preferably, is sharpened as indicated at 25 to form a tear-off edge. Also, the lower thickness of the blade is provided with slots 26, to register with the slots 18^a through which the register-pins may project. 75

A multiple carbon roll 30 is supported in a canister 31 which is attached to one of the side walls 17 and is provided with a door 31^a. Carbon strips 30^a may be drawn from the canister around the edge of the door 31^a and over the platen A², interleaved with the stationery strips 14^a. The flanges 22 of the cover member help to clamp the carbon strips in position. Near the rear of the platen, carbon protecting aprons 32 may be supported in interleaved relation with the strips 14^a and are adapted to overlie and underlie the edge portions of the carbon strips so as to prevent their being torn when the stationery is advanced. The aprons may be supported in any suitable manner such as by flat metal strips 33 which project beyond the edges of the stationery strips and float between said strips. A leaf spring 34 is attached to the cover B by means of a rivet 34^a and presses the interleaved stationery down against the platen. 90

In order to press the strips 14^a together at the front of the machine during the manual withdrawal of the stationery the presser device C is provided, which comprises an upper presser roll 36 which is journaled in a housing member 37 which is rigidly attached to the bar B'; and a lower presser roll 38 which is journaled in a bifurcated arm 39 carried by a rock shaft 40 which is journaled in the side walls of the casing. A coil spring 41 urges the roll to its uppermost position. The platen A² is provided with a slot 42 which permits the roll 38 to engage and 110

press the stationery against the companion roll 36.

No invention is claimed herein for the use of presser-rolls, which are the invention of Louis 5 Barker, and shown in his co-pending application, Serial No. 635,427, filed September 29, 1932. Applicant, however, has invented the present mechanism for retracting the lower presser roll 38 while the stationery is being advanced by 10 movement of the register-pins.

The initial feed mechanism D includes a rock shaft 45, journaled in the side walls of the casing and is provided with an integrally formed actuating arm 45^a and register-pin supporting arms 45^b. A spring 45^c on the shaft 45 tends to rock the arm rearwardly and the swing of arm 45^a is limited by a front stop 17^a and a rear stop 17^b fixedly mounted on the sidewall of the casing. A pair of register-pins 47 are telescopically mounted on the arms 45^b and are projected upwardly by means of compression springs 48. A pin-retracting rock-shaft 50 is provided with rearwardly extending arms 50^a which are adapted to bear against the curved portion 18 25 of the platen A² and engage flanges 47^a provided on the register-pins. The arms 50^a are urged downwardly by means of a coil spring 51. The rock shaft 50 has an actuating arm 50^b which is normally held in its upper position by means 30 of a trigger member 52 which is pivoted to the side wall of the casing at 52^a and is urged forwardly by means of a spring 52^b. The rock shaft 45 is provided on the inside of the casing with a cam-member 53. The upper portion of the 35 cam 53^b is designed to engage the arm 50^b and raise it to its uppermost position, while the pins 47 are permitted to return to their normal strip engaging position. The arm 50^b is held in the upper position, by means of the trigger-member 40, until the pins are rocked to their extreme forward position, at which time the butt portion of the cam 53^c will engage the trigger-member and cause the release of the arm 50^b. It will be understood that this action will cause the 45 arms 50^a to sweep the pins 47 from the perforations in the stationery. The cam 53 is further provided with a stub-shaft 54 which may project through a slot 55 in the side wall of the casing, and is equipped on the outside of the 50 casing with a roller 56 which is adapted to engage an operating arm 40^a and cause the lower presser-roller 38 to be depressed when the register-pin shaft 45 is rocked forwardly.

In operation, feed is initiated by rocking the 55 shaft 45 forwardly. The pins draw the paper from under the tear-off blade B' until they are swept from engagement with the stationery by the arms 50^a, whereupon they will be permitted to swing back and bear against the lower side 60 of the paper until they encounter the next set of register perforations in the strips which may be drawn forwardly by hand. At the same time the shaft 45 is rocked forwardly the lower presser-roll is depressed through the action of 65 roller 56 on the arm 40^a.

In the modification shown in Figs. 5-7 continuous-form stationery strips are drawn over a platen 60, which is equipped at its front end with longitudinal slots 60^a, and are engaged by 70 yieldingly urged register-pins which are disposed beneath a stationary tear-off bar 61 which is equipped at its lower side with slots 61^a. A rock-shaft 62 is journaled in the side walls of the casing of the machine and is provided with a 75 pair of arms 62^a in which a register-pin sup-

porting rock-shaft 63 is journaled. The shaft 63 extends through a slot 64 in the side wall of the casing and is provided with an operating arm 63^a. The shaft 63 is further provided with an arm 63^b (shown dotted) to which is attached a tension spring 65 which urges the shaft 63 upwardly and the arm 63^a rearwardly against a stop on the outside of the casing. The shaft 63 is further provided with register-pin supporting arms 63^c upon which are telescopically mounted the register pins 66. The sleeve portion of the pins 66 is provided with a slot 66^a which is engaged by a pin 63^d on the arm 63^c, to permit limited movement between the members. The pin-members are further provided with a flange portion 66^b which limits the projection of the pins through slots 60^a. Compression springs 67 urge the register-pins to their extended position. Referring to Figs. 6 and 7, it will be seen that the casing is equipped near its upper front corner with a fixed cam-member 68 having a projection 68^a disposed in the path of a stud 69 which is fixedly mounted on the arm 63^a. The member 68 is recessed at 68^b so that the stud 69 can make a cyclic movement around projection 68^a. The member is further provided with a rear stop 68^c and a front stop 68^d so that the movement of the arm 63^a is entirely limited by the member 68 and the slot 64 in the side wall of the casing.

In operation, after a set of forms have been 105 filled in the shaft 63^a is rocked forwardly, so as to advance the stationery strips from under the tear-off bar 61, until the arm engages the stop 68^d, whereupon the entire rock shaft 63 is moved downwardly bodily in the slot 64 and the pins are rocked back to strip engaging position. It will be seen that the member 68^a prevents withdrawal of the register-pins during this forward movement and serves also to hold the pins in retracted position while being rocked back to strip engaging position. The spring 65 is so arranged as to urge the shaft 63 to its uppermost position in the slot 64 and also to rock the pins to the normal strip engaging position shown in Fig. 5.

Another modification is shown in Figs. 8-10 wherein the stationery strips are drawn over a platen 70, having longitudinal slots 70^a, and under a tear-off bar 71. In this form a rock shaft 72 equipped with an actuating arm 72^a is provided with a U-shaped member 73 which is urged rearwardly by means of a tension spring 74. A pair of register pins 75 are supported on the member 73 by means of leaf-springs 75^a. A cross bar 76 is attached to the front portion of the springs 75^a and extends across the inside of the casing to engagement with ratchet-members 78 which are fixedly mounted on the side walls of the casing. The bar is equipped with teeth 76^a which are adapted to engage the ratchets 78 and prevent rearward movement thereon. A tension spring 79 is attached to the bar 76 and is so positioned as to be slack, when the pins are in the position shown in Fig. 8, so that the leaf-springs 75^a will project the pins 75 upward to strip engaging position.

It will be understood that when the pins are moved forwardly by manual operation of the arm 72^a, the bar 76 will ride on the ratchets 78 until the pins reach their foremost position. During this movement the spring 79 is placed under increasing tension and when the bar 76 reaches a position beyond the ratchets the spring will have sufficient strength to retract the pins from strip engagement. Upon the return stroke the bar 76 15

will ride on the lower side of the ratchet members 78. to normal strip engaging position.

The mechanism illustrated in Fig. 11 is similar to that in Figs. 8-10 and similar reference numbers are used, except for a leaf-spring 80 which is employed instead of the tension-spring 79 shown in the other figures. The spring 80 may be attached to the front wall of the casing by means of a rivet 80^a and its rear end portion is 10 free to bear against the lower side of the platen. When the pins are advanced the spring 80 will be bowed upwardly and after the bar has passed the ratchet-pieces the spring will force the pins from engagement with the stationery by pressing 15 the cross bar beneath the ratchet.

In each of the illustrated constructions, means for actuating the pin-carrying rock-shaft and controlling the retraction of the pins are provided, such means including an actuating-arm 20 carried by one end of the rock-shaft. Thus, an extremely simple mechanism will serve the purpose, although such mechanism may involve various embodiments.

The foregoing detailed description has been 25 given for clearness of understanding only, and no unnecessary limitations should be understood therefrom, but the appended claims should be construed as broadly as permissible, in view of the prior art.

30 What I regard as new, and desire to secure by Letters Patent, is:

1. In an autographic register: a casing; a platen mounted on said casing over which stationery-strips provided with register-perforations may be drawn from the rear, said platen being provided near its front end with slots; a tear-off blade mounted above said platen and having slots registering with the slots in said platen; a rock-shaft extending across the front 40 portion of said casing and having an actuating arm outside of the casing; register-pins mounted on said rock-shaft and yieldingly urged through the slots in said platen and tear-off blade to engage the perforations in said stationery; and 45 guide means adapted to hold the pins retracted from the stationery-strips while said shaft is rocked rearwardly.

2. In an autographic register: a platen having near its front end register-pin openings; and an 50 initial-feed device comprising a rock-shaft equipped with an operating handle and register-pins yieldingly urged through said openings and adapted to move forwardly therein, and means for abruptly retracting said pins near the front 55 end portion of the working stroke of said shaft and for holding said pins retracted during a greater portion of the return stroke.

3. A device as specified in claim 2, in which the 60 means for retracting the pins comprise arms in slidable engagement with said pins and cam-operated mechanism for actuating said arms in timed relation to the oscillation of said rock-shaft.

4. In an autographic register having a casing 65 provided with a platen, an initial feed device comprising: a rock-shaft provided with yielding register-pins projecting normally above said platen, an actuating arm adapted to retract said pins below the platen, a spring urging said arm 70 to pin-retracting position, a latch serving to hold said arm in inoperative position, means for moving the arm into engagement with said latch, and means for unlatching said arm when the pins are near the front end of their working stroke.

75 5. Mechanism as specified in claim 4, in which

the means for moving the actuating arm into latching position comprises a cam mounted on the rock-shaft.

6. Mechanism as specified in claim 4, in which the unlatching means comprise a cam which is mounted on the rock-shaft and is adapted to move the latch from engagement with the actuating arm when said rock-shaft is rocked to its forward position.

7. An autographic register comprising: a casing having a platen-forming top; a rock-shaft journaled in said casing and equipped with normally projected extensible register pins adapted to engage perforations in stationery-strips led over said platen; a rock-shaft upon which a presser-roll adapted to press said stationery strips together is eccentrically mounted. said rock-shaft being equipped with an arm for swinging the presser-roll from operative engagement with the strips; and a cam on the register-pin rock-shaft in engagement with said arm and serving to retract the presser-roll when the register-pin shaft is rocked forwardly.

8. Mechanism as set forth in claim 7, in which an arm is provided for retracting the register-pins, a latch is provided to hold said arm in inoperative position, and said cam serves to unlatch the pin-retracting arm when the register-pin rock-shaft is oscillated to its forward position, and said cam serves also to reset the arm in latched position when the shaft is oscillated back to its normal position.

9. In an autographic register having a casing provided with a platen, an initial feed device comprising: a rock-shaft equipped with register-pins yieldingly urged above said platen, and guide means adapted to prevent withdrawal of the pins during a portion of their forward stroke and adapted to prevent the pins from being further projected during a portion of their rearward stroke.

10. Mechanism as specified in claim 9, in which spring means are provided for automatically retracting said pins near the end of their forward stroke.

11. Mechanism as specified in claim 9, in which ratchet and pawl means are provided to prevent rearward movement of the pins while projecting through said slots.

12. In an autographic register; a casing having a platen forming top; a rock-shaft journaled in the front portion of said casing and provided with normally projected register-pins adapted to engage perforations in stationery led over said platen; and means restraining retraction of said pins during the main portion of their forward traverse, permitting their retraction near the conclusion of such movement, and preventing their projection during the first portion of the return stroke.

13. Mechanism as specified in claim 12, in which said means comprise an arm attached to said register pins, and a guide-member mounted on said casing to direct the movement of said arm.

14. In an autographic register: a casing having a platen thereon, a rock-shaft journaled in said casing and provided with arms, an actuating rock-shaft journaled in the arms on said rock-shaft and equipped with an actuating handle, yieldingly urged register-pins mounted on said actuating rock-shaft and adapted to project above said platen, and means adapted to hold the register-pins projected or retracted with respect to the platen during a portion of the stroke of said rock-shaft.

15. Mechanism as specified in claim 14, in which the means for holding the register-pins projected or retracted during the movement of said rock-shaft comprises a boss mounted upon the casing 5 and engaged by a stud on the actuating handle so that the stud may make a cyclic movement about said boss.

16. In an autographic register: a casing having a platen forming top; a rock-shaft journaled in 10 the front portion of said casing and provided with normally projected register-pins adapted to engage perforations in stationery led over said platen, said rock-shaft being further provided with an operating handle outside of said casing; 15 and means restraining retraction of said pins during the major portion of their forward traverse, permitting their retraction near the conclusion of such movement, and preventing their projection during the first portion of the return stroke.

20 17. In an autographic register: a frame having a platen over which stationery strips provided with register perforations may be led; and an initial feed device comprising a register pin yieldingly urged into engagement with said perforations and 25 mounted for forward and rearward movement with respect to said platen, a transversely disposed oscillatable rock-shaft journaled in said frame and equipped with an operating handle,

means on said shaft for moving said pin forwardly, means for retracting the pin from engagement with the perforations near the forward end of its movement and holding the pin retracted during the first portion of its return movement, and means for limiting the oscillation of said rock-shaft.

18. In an autographic register: a frame having a platen over which may be led continuous-form stationery having forms provided near their front ends with pairs of register perforations; and an initial feed device comprising a transversely disposed rock-shaft journaled in said frame and equipped externally with an actuating handle, normally projected spring-supported register pins 90 adapted to engage said pairs of perforations in succession, said pins being actuated through the medium of said rock-shaft to effect an initial feed of the stationery; co-acting means for withdrawing said pins near the end of the initial feed movement and holding them retracted during the first portion of the return stroke, and means for limiting the oscillatory movements of said rock-shaft.

19. Structure as specified in claim 18, combined with spring means for returning the rock-shaft and pins to feed-initiating position.
